CHARLES F. MASSEY, OF CHICAGO, ILLINOIS, ASSIGNOR TO MASSEY CONCRETE PRODUCTS CORPORATION, OF CHICAGO, ILLINOIS, A CORPORATION OF VIRGINIA.

METHOD OF AND APPARATUS FOR REMOVING CONCRETE POLES FROM THEIR MOLDS.

1,315,733.

Specification of Letters Patent.

Patented Sept. 9, 1919.

Application filed July 11, 1919. Serial No. 310,095.

To all whom it may concern:

Be it known that I, CHARLES F. MASSEY, a citizen of the United States, residing at Chicago, in the county of Cook and State 5 of Illinois, have invented certain new and useful Improvements in Methods of and Apparatus for Removing Concrete Poles from Their Molds, of which the following is a specification.

10 This invention relates to a method of and apparatus for removing concrete poles and the like from their molds, and it has for one of its primary objects, the provision of an improved method and apparatus whereby 15 the poles may be removed from their molds, or vice versa, without taking the mold apart, and the cost of production greatly reduced.

In general, my invention contemplates the provision of an improved method and apparatus whereby I expand the metal mold by the application of steam or some other heating medium, thus permitting withdrawal of the mold from the pole.

The foregoing, together with such other 25 objects as may hereinafter appear, I obtain by means of an improved method and apparatus which I have illustrated in the accompanying drawings wherein. The figure is a partial section and side elevation of the 30 apparatus I employ in carrying out my improved method, and from which the latter may be readily understood.

The molds used in making concrete poles, either by hand methods or by centrifugal 35 machine methods, are usually of sectional character, that is to say, they are comprised of two half molds each composed of a plurality of half mold sections, such sections being bolted or otherwise secured together to 40 constitute the half molds and the half molds being adapted to be bolted together to form the complete mold. Heretofore, after the completion of a pole, in order to remove the pole from the mold, it was necessary to unbolt the two half molds, which of course necessitates the rebolting together of the 45 two half molds for the casting of another pole. These operations involve considerable labor and time and also require a large 50 amount of floor space, as a result of which the cost of production is quite high. I pro-

pose to overcome these difficulties by making it possible to remove the pole without taking the mold apart.

In carrying out my invention, I provide a 55 narrow pit 7 of considerable length and depth, at one upper edge of which, I pivotally mount a frame 8, in such manner that the free end of the frame may be swung downwardly into the pit until the frame assumes a substantially vertical position in 60 the pit. Upon the formation of a hole in its mold, either by hand or by machine, I place the mold upon the frame 8 by suitable mechanism such as a crane or a hoist, 65 and clamp the mold in position on the frame by means of suitable clamping devices, such as the strap members 9. The mold is placed in position on the frame with the tip end toward the pivot and the butt end adjacent 70 a block 10 carried by the frame.

The frame 8 is shown in mold receiving position in full lines in the figure, and after the mold has been properly positioned and clamped, the free end of the frame is lowered by such means as the windlass 12, for example. Before lowering, the end closure plate 11 is removed from the mold, leaving the butt end thereof open. When the frame 8 has been lowered to a position when the 80 center line of the mold is perpendicular, the bottom of the mold and the butt end of the pole will be immediately over the flattened surface 13.

With the mold in the dotted line position, 85 steam is admitted to the pit 7 through the pipe 15 and the mold is thereby heated and owing to the fact that it gets hot first and to the fact that metal has a higher coefficient of expansion than concrete, the mold expands sufficiently to free it from the pole which settles on the flat surface 13. The mold with the frame 8 may now be withdrawn from the pole by elevating them by such means as the cable 16 which is hooked 90 to the casting 17 of the frame.

In order to permit of the elevation of the mold and frame, the hinge 18 for the frame 8 is detachably secured to the foundation by means of bolts 19 or the like, which are taken 100 off previous to elevation.

If desired, after a mold has been placed

2
in position on the frame 8, a plate like member 20 may be detachably secured to the frame, such plate having a width slightly less than the width of the pit, and acting, when the frame has been swung to the dotted line position to form a relatively small chamber 7^a into which the steam from pipe 15 is introduced. This arrangement effects a great saving in steam.

10 I claim:

1. The herein described process which consists in forming a concrete pole or the like in a metallic mold, in applying heat to the mold to expand the same, and in withdrawing the mold.
- 15 2. The herein described process which consists in forming a concrete pole or the like in a metallic mold, in applying heat to the mold to expand the same, and in withdrawing the mold from the pole perpendicularly.
- 20 3. The herein described process which consists in forming a concrete pole or the like in a metallic mold, in suspending the mold in vertical position, in expanding the mold

by the application of heat thereto, and in withdrawing the mold from the pole.

4. The herein described process which consists in forming a concrete pole or the like in a metallic mold, in supporting the mold in a chamber in perpendicular position and against movement, in introducing a heating medium into said chamber, and in withdrawing the mold from the pole vertically.

5. Apparatus for separating a concrete pole or the like and its metallic mold which consists of a suitable frame, adapted to support the mold, a chamber into which said frame may be moved, and means for heating the mold.

6. Apparatus for separating a concrete pole or the like from its metallic mold which comprises a pit, a frame adapted to support said mold and to be lowered into said pit, means for heating the mold, and means for withdrawing the mold from the pole.

In testimony whereof, I have hereunto signed my name.

CHARLES F. MASSEY.
